UNITED STATES PATENT OFFICE.

FREDERIC W. PENDERGAST, OF ROCHESTER, VERMONT.

CARRIAGE-SEAT.

SPECIFICATION forming part of Letters Patent No. 280,509, dated July 3, 1883.

Application filed April 9, 1883. (No model.)

To all whom it may concern:

Be it known that I, FREDERIC W. PENDERGAST, of Rochester, in the county of Windsor and State of Vermont, have invented a new and Improved Spring-Back for Carriage and Sleigh Seats, of which the following is a full, clear, and exact description.

My invention relates to that class of backs for carriage and sleigh seats which are supported in position by means of spring-arms; and it consists of the combination and arrangement of parts, substantially as hereinafter fully set forth and claimed.

Reference is to be had to the accompanying drawings, forming part of this specification, in which similar letters of reference indicate corresponding parts in all the figures.

Figure 1 is a perspective view of a carriage or sleigh seat having a spring-back contrived according to my invention. Fig. 2 is an end elevation of a portion of the seat with a part in section. Fig. 3 is a rear elevation of a portion of the seat-back, partly in section, the latter showing the contrivance of the pivot-joint.

The lower edge of the seat-back *a* terminates in a bar, *b*, which has a metal cap, *c*, on each end, from which a pivot, *d*, projects, preferably near the lower side, to support the seat-back in bearings *e*, formed on the rear ends of bars *f*, extending across the top of the seat *g* to the front, and being suitably bolted to it for holding the pivots.

For holding up the seat-back against the rear ends of the end pieces, *h*, of the seat, so as to allow the back to yield to the thrusts of the seat and afford comfortable support to the rider, I employ spring-arms *i*, of suitable strong spring-wire, which I connect to the back, about midway between the top and bottom, by eye-studs *j*, screwed into or otherwise attached to the back, and projecting from the hind side

thereof near the ends, the said spring-arms being bent therefrom around the ends of the back and extended forward alongside of the seat ends *h*, near to the front of them, where they are coiled suitably at *l* for the proper elasticity, and then connected with the seat by screw-threaded portion, *m*, extending through the seat and secured by a nut, *n*, or equivalent device.

The bars *f* are to be detachably secured to the seat for being readily taken off when required for shifting the back from one seat to another.

The seat-back may be plain or upholstered as may be preferred, and it may be made high than ordinary backs in consequence of the yielding arrangement, thereby affording high support to the back of the rider, besides being also yielding thereto.

I desire it to be understood that the frame of the seat-back is to be made either of wood or metal, at the will of the constructor.

Having thus described my invention, what I claim as new, and desire to secure by Letters Patent, is—

The combination, with the back *a*, provided with pivots *d* at its lower corners, and the bars *f*, having bearings *e*, and fastened to the seat *g*, of the spring-arms *i*, connected to the rear side of the back *a* by eye-studs *j*, and being around the ends of the back, extended along and below the ends of the seat, and coiled thereat and connected to the seat, the ends of the said arms being screw-threaded, substantially as shown and described, and for the purpose set forth.

FREDERIC W. PENDERGAST.
